V. G. TORNQUEST.
METALLIC RAILWAY TIE.
APPLICATION FILED MAR. 8, 1913.

Patented Aug. 12, 1913.

UNITED STATES PATENT OFFICE.

VERNER G. TORNQUEST, OF CALUMET, MICHIGAN.

METALLIC RAILWAY-TIE.

1,070,305.

Specification of Letters Patent. Patented Aug. 12, 1913.

Application filed March 8, 1913. Serial No. 753,047.

To all whom it may concern:

Be it known that I, VERNER G. TORNQUEST, a citizen of the United States, residing at Calumet, in the county of Houghton, State of Michigan, have invented new and useful Improvements in Metallic Railway-Ties, of which the following is a specification.

This invention relates to new and useful improvements in metallic railway ties and fastenings for the rails and more particularly to that class of such devices in which are employed two heads and a connecting or tie bar with means for attaching the rails to the heads.

The present invention has for its object, among others, to provide an improved tie of this character which will be light, though strong, cheap and durable, and by means of which the rails may be easily and quickly secured in position, yet held against all tendency to become accidentally displaced. The tie serves to effectively hold the track in line, the connecting bar of the tie plate as well as the legs of the heads being embedded in the roadbed.

The improvement further consists in the combination, construction and operative arrangement of parts set forth in the following description and falling within the scope of the appended claims.

In the drawing, which illustrates a satisfactory reduction of my improvement to practice, Figure 1 is a perspective view of a pair of rails supported upon my improved tie, Fig. 2 is a central vertical longitudinal sectional view through the same, the ties being arranged within the roadbed, Fig. 3 is a perspective view of a head member disconnected from the connecting plate, and Fig. 4 is a view of the nut and bolt employed for securing the rails upon the tie. Fig. 5 is a detail elevation illustrating the bar 12 and one of the foot members 5 provided with co-acting serrations or teeth.

The improved tie embodies essentially two head members 1 and a connecting bar or plate 12. Each of the heads 1 is of a similar construction, and embodies a top plate 2 which has its ends provided with depending legs 3 and 4, each of which has its extremity formed with outset feet 5 and 6. The leg 3 is arranged at a right angle to the body, and its foot 5 is arranged at a right angle to the leg. The leg 4 is inclined outwardly from the top or connecting plate 2, while its

foot 4 is arranged in a plane substantially even with the horizontally disposed connecting bar or plate 12. The top 2 may be of a greater thickness than the legs and feet, or the said top 2 may have integrally formed therewith enlargements which are disposed a suitable distance from the center of said portion 2 to provide for the reception of the base flanges of the rails R. The shoulders 7 provided by the enlarged portions of the head are adapted to frictionally engage with the longitudinal edges of the base flanges of the rails R, and the portion 2 of each of the heads is provided, at diagonally opposite points with suitable openings 8. These openings are adapted for the reception of headed members 9 having threaded shanks 10. The heads 9 are preferably projected only upon one side of the shank 10, the said projecting portion being shaped to agree with the cross sectional shape of the base flange of the rails with which they are adapted to contact.

The numerals 11 designate nuts which engage with the shanks which extend below the connecting member 2 of the heads 1, and whereby the heads 9 may be secured in tight frictional engagement with the base flanges of the rails.

By the peculiar arrangement of the legs 3 and 4 of the heads 1, it will be noted that when the roadbed has been tamped around the same, the heads will be prevented from movement in any direction.

In order to properly space the heads 1 to receive the rails of the track, I employ a tie plate or connecting bar 12. This bar embodies a flat rectangular member which may be of a width equaling the width of the heads 2, or may be of a lesser width if desired. The connecting bar is formed, adjacent its ends, with elongated slots 13, and the feet 5 are provided with bolt openings 14 for the reception of bolts 15 which pass therethrough and through the elongated slots 13. The bolts 16 are employed for retaining the tie bar upon the feet 5 of the heads. It will be noted that the tie bar 12 is disposed below the feet, and that by providing the tie bar with elongated slots 13, the heads may be moved toward or away from each other in proper spaced relation to agree with the gage of the tracks. However, if desired, I may provide one or both of the faces of the tie bar 12 adjacent the ends thereof with depressions or teeth 17, and

likewise provide the underfaces of the feet 5 with serrations providing teeth 18 which may engage with the teeth 17 of the tie bar 12, and thus entirely overcome the danger of 5 accidental displacement of the said bar from engagement with the feet 5 of the heads 1.

Having thus described the invention, what I claim as new is:

1. A metallic tie for railroads comprising 10 two heads, each of said heads including a top plate having its ends formed with downturned legs, and the legs provided with outwardly extending feet, the inner leg of each of the heads being arranged at a right angle 15 to the top bar of the head, the outer leg of each of the heads being arranged at an outward angle from the top or connecting bar of the head, the feet of the inner legs being provided with openings, a tie rod having elongated slots adjacent its ends and adapted 20 to be disposed below the feet of the inner legs of the head, bolts in the openings in the feet and in the tie bar, a nut for each of the bolts, means for securing the rails to 25 the connecting plates of the heads and the legs of the heads of the tie bar adapted to be embedded within the roadbed of the track.

2. In a metallic tie for railroad rails, two heads, each of said heads comprising a top plate which is formed with a rail passage for 30 the reception of the rail, means embodying headed bolts for securing the rails within the passages, each of the said plates having downturned legs at their ends, each of the legs being provided with out-turned feet, the 35 outer leg being arranged at an outward angle from the top plate of the head, the feet of the inner leg members having their underfaces serrated, a connecting bar, said connecting bar having one of its faces adjacent 40 its ends serrated to provide teeth which are adapted to engage with the teeth of the feet, means for longitudinally adjusting the connecting bar with relation to the heads, means for securing the connecting bar to the inner 45 feet of the heads, and the feet and legs and connecting bar adapted to be buried within the roadbed of the track.

In testimony whereof I affix my signature in presence of two witnesses.

VERNER G. TORNQUEST.

Witnesses:

CHARLES SWANSON,
HYALMAR KJELLGREN.
